HOLDER FOR TOAST OR THE LIKE

William F. Bradley, 5841 Nagle Ave.,
Van Nuys, Calif. 91461

Filed Mar. 29, 1967, Ser. No. 6,426

Term of patent 14 years

(Cl. D44—1)

FIG. 1 is a front perspective view of a holder for toast or the like, showing my new design;

The dominant features of the design reside in the portions shown in full lines.

I claim:

The ornamental design for a holder for toast or the like, substantially as shown and described.
